HOCKEY STICK

Zachariah Adam Hall, Guelph, Ontario, Canada

Application August 15, 1932, Serial No. 628,805

7 Claims. (Cl. 273—67)

It is well known amongst hockey players and others that the weight of a hockey stick is an important factor in fatiguing a hockey player during a game and thereby slowing his speed. The ability 5 to lighten the weight of hockey sticks heretofore used by one, two or even three ounces without sacrificing the rigidity of the stick was greatly desired as it would give the player a much lighter load to carry. Since the player usually carries 10 his stick extending in front of him, the actual saving on the player by a decrease in the weight of the stick by say two ounces will be approximately twelve ounces.

It is also well known that a rigid shaft is highly 15 desirable in a hockey stick but heretofore this feature was dependent solely on the kind and quality of the wood used in the manufacture and it had certain limitations such as the weight desired for the finished stick. To lighten the sticks 20 heretofore in use, it was necessary to remove the necessary amount of wood from the handle which had the effect of decreasing its rigidity.

The object of this invention is to construct a 25 hockey stick whereby the balance of the stick may be improved by altering its weight without changing the size or dimensions of the stick. A further object of this invention is to increase the rigidity of the shaft without adding to the weight of the stick. These and other objects of the invention 30 are accomplished by a laminated construction whereby the balance of the stick is improved without altering its weight or changing the size or dimensions of the stick. A further advantage of a stick constructed according to this invention 35 is that the rigidity of the shaft can be increased without adding to the weight of the stick. A still further advantage is that warping of the stick is nullified to an extent which permits it being kept indefinitely without serious impairment 40 of its quality or grade.

Other and further objects and advantages of a 45 hockey stick constructed according to this invention will be apparent by reference to the following description and accompanying drawing in which:—

Fig. 1 is a front elevation of a hockey stick embodying my invention;

Fig. 2 is a cross sectional view on the lines 2—2 Fig. 1;

Fig. 3 is a sectional view on the line 3—3 Fig. 1; and

Fig. 4 is a perspective view showing the insert extended to the heel of the stick.

Like characters of reference refer to like parts 55 throughout the specification and drawing.

The subject matter of my invention comprises an integrally formed shaft and head sawn out of a flat billet which has been bent in the manner well known to the art to the required shape and which has substantially parallel faces. In the 5 preferred construction the hockey stick comprises a shaft 1 having substantially parallel faces and a blade 2 of the usual dimensions extending at an angle thereto. The shaft 1 is provided with a channel 3 which extends from front to back of 10 the handle and inwardly from its free end to approximately the throat 5 of the stick as shown in Fig. 1 or to the heel of the stick as shown in Fig. 4, the sides of the channel being substantially 15 parallel to said faces. Wedge shaped insert 6 having an upper butt end wider than the channel is entered in the channel and glued or otherwise fastened thereto. The insert may be made of wood the same or different to that of which 20 the stick is made. The kind of wood depending on the weight and rigidity desired.

When it is desired to produce a stick lighter than could be attained if the stick was made of the same material throughout, an insert made of a lighter wood is required. The weight of the 25 stick may be still further reduced by removing part of the insert by a series of perforations 7, as shown in Fig. 2, but the perforations may be omitted or the number increased or decreased as desired.

In every instance where the hockey stick has 30 been so constructed, the rigidity of the shaft has been increased over what it would have been had the shaft not been of a laminated construction. Further, the weight of the stick can be readily ad- 35 justed in the course of manufacture to the necessary requirements, thereby improving its balance. Another advantage of this construction is that the grade or quality of the stick can be raised to a higher standard than could be attained if the 40 stick was not so made. That is a second grade stick can be raised to a first grade stick and so forth. This means a substantial saving in material as material which is not suitable for the particular grade manufactured may be used without impairing the grade or quality of the manufactured stick.

Having thus fully described my invention what I claim as new and desire to secure by Letters 45 Patent is:

1. A hockey stick comprising a shaft and a blade integrally formed, the blade extending at an angle to the shaft, a channel extending inwardly from the free end of the shaft and an insert constituting an essential part of the shaft 55

entered in the channel and secured to the sides thereof and provided with a perforation for improving the balance of the stick by decreasing the weight of the shaft.

- 5 2. A hockey stick comprising an integrally formed shaft and head sawn out of a flat billet bent to the required shape, the shaft having substantially parallel faces, a slot in the shaft extending from the front edge to the rear thereof and from the top of the shaft to the heel of the stick, the sides of said slot being substantially parallel to said faces and a wedge shaped filler member having an upper butt end wider than the slot for adjusting the balance and weight of the shaft and expanding the shaft to the desired width secured in and filling said slot.
- 10 15

3. A hockey stick comprising an integrally formed head and shaft sawn out of a flat billet bent to the required shape having substantially parallel faces, a slot in the shaft extending from the front edge to the rear edge thereof and from the top of the handle to the throat of the stick, the sides of the slot being substantially parallel to said faces and a wedge shaped filler member having an upper butt end wider than the slot for adjusting the balance and weight of the shaft and expanding the shaft to the desired width, secured in and filling said slot.

- 20 25 4. A hockey stick comprising an integrally formed shaft and head sawn out of a flat billet bent to the required shape, the shaft having substantially parallel faces, a slot in the shaft extending from the front edge to the rear edge thereof and from the top of the shaft to the throat of the stick, and a wedge shaped filler member having an upper butt end wider than the slot for adjusting the balance and weight of the shaft and expanding the shaft to the desired width, secured in and filling said slot.
- 30 35

expanding the shaft to the desired width, secured in and filling said slot.

5 5. A hockey stick comprising an integrally formed head and shaft having substantially parallel faces, a slot in the shaft extending from the front edge to the rear edge thereof and from the top of the shaft to the heel of the stick, the sides of said slot being substantially parallel to said faces and a wedge shaped filler member having an upper butt end wider than the slot for adjusting the balance and weight of the shaft and expanding the shaft to the desired width secured in and filling said slot.

10 15 6. A hockey stick comprising an integrally formed shaft and head sawn out of a flat billet bent to the required shape, the shaft having substantially parallel faces, a slot in the shaft extending from the front edge to the rear edge thereof and from the top of the shaft downwardly towards the throat of the stick, and a wedge shaped filler member having an upper butt end wider than the slot for expanding the shaft to the desired width secured in and filling said slot.

20 25 7. A hockey stick comprising an integrally formed head and shaft sawn out of a flat billet bent to the required shape having substantially parallel faces, a slot in the shaft extending from the front edge to the rear edge thereof and from the top of the handle downwardly towards the throat of the stick, the sides of the slot being substantially parallel to said faces and a wedge shaped filler member having an upper butt end wider than the slot for adjusting the balance and weight of the shaft and expanding the shaft to the desired width, secured in and filling said slot.

30 35 ZACHARIAH ADAM HALL.
